(57) **CLAIM**

The ornamental design of an element of an aircraft, as shown and described.

DESCRIPTION

FIG. 1 is a top, front, right side perspective view of an element of an aircraft showing my new design;

FIG. 2 is a bottom, rear, right side perspective view thereof;

FIG. 3 is a right side elevation view thereof;

FIG. 4 is a top plan view thereof;

FIG. 5 is a bottom plan view;

FIG. 6 is a top, front, right side perspective view of the element of an aircraft shown applied to an aircraft; and,

FIG. 7 is a top, rear, left side perspective partial view thereof.

Throughout the Figures, broken lines showing environment or structure are for illustrative purposes only and form no part of the claimed design.

1 Claim, 4 Drawing Sheets
